DESIGN FOR A SLICING MACHINE

George R. Wood, Montreal, Quebec, Canada

Application June 26, 1941, Serial No. 101,709

Term of patent 14 years

To all whom it may concern:

Be it known that I, George R. Wood, a citizen of Canada and subject of the King of Great Britain, residing at Montreal, in the Province of Quebec, Dominion of Canada, have invented a new, original, and ornamental Design for a Slicing Machine, of which the following is a specification, reference being had to the accompanying drawing, forming a part thereof.

Figs. I, II and III of the drawing are perspective views of the slicing machine of my new design, taken from different angles.

I claim:

The ornamental design for a slicing machine, as shown.

GEORGE R. WOOD.
